TABLE LIGHTER

Curt Heuckeroth, Steinbach, near Michelstadt, Odenwald, Germany, assignor to Rowenta Metallwarenfabrik G.m.b.H., Offenbach (Main), Germany, a company of Germany

Filed Oct. 15, 1964, Ser. No. 82,182

Term of patent 14 years

(Cl. D48—27)

FIG. 1

FIG. 2

FIG. 3

FIG. 4

FIG. 5

FIG. 6

FIG. 1 is a top view of the table lighter showing my design;

FIG. 2 is a left-hand elevational side view of the table lighter;

FIG. 3 is an elevational front view of the table lighter;

FIG. 4 is an elevational right-hand side view of the table lighter;

FIG. 5 is a bottom view of the table lighter; and

FIG. 6 is an elevational rear view of the table lighter.

The surface pattern dominating the lower portion in FIGS. 2, 3, 4 and 6 is indicative of a textured finish only.

I claim:
The ornamental design for a table lighter, as shown and described.
